UNITED STATES PATENT OFFICE

ELBRIDGE G. HADEN, OF CHARLOTTESVILLE, VIRGINIA

FLUSH VALVE

Application filed January 5, 1931. Serial No. 506,778.

My invention relates to improvements in flush valves for water-closets, and the like, and it consists in the combinations, constructions and arrangements herein described and claimed.

An object of my invention is to provide a valve of relatively simple construction which can be made at a low cost, but which will operate efficiently for flushing the bowl in a water-closet.

Another object of the invention is to provide a device which obviates the necessity of floats and similar devices which render the construction complex, and which is liable to get out of order.

A further object is to provide a valve which may control the inflow of water into the tank, and which also controls the water from the tank to the bowl when it is desired to flush the latter, thereby providing a valve having a double function.

A further object of the invention is to provide means whereby, when the valve is in its normal position, adequate drainage is provided, so as to prevent danger to the tank, as by freezing and bursting.

Other objects and advantages will appear in the following specification and the novel features of the invention will be particularly pointed out in the appended claim.

My invention is illustrated in the accompanying drawings forming part of this application, in which:

Figure 1 is a side view of a water-closet with my invention applied thereto.

Figure 2 is an enlarged longitudinal sectional view of the valve.

Figure 3 is a section along the line 3—3 looking in the direction of the arrows.

Figure 4 is a perspective view of the cylindrical valve member.

Figure 5 is a perspective view of the operating handle, and,

Figure 6 is a side view of a modified form

of water closet with my invention applied thereto.

In carrying out my invention I provide a valve best illustrated in Figs. 2, 3 and 4. This consists of a casing 1 having a central longitudinal cylindrical bore extending from end to end. The casing is preferably provided at the ends with reduced portions 1a, which are threaded to receive caps 2. The latter are recessed as shown at 3 to provide packing glands. Registering openings 4 are disposed in the casing 1 and pipes 5 and 6 have their ends disposed in the opposed openings as shown in Fig. 2.

The cylindrical valve member is shown in Fig. 4. It consists of a cylindrical body portion 7 having reduced end portions 8. The body portion 7 has a passageway 9 extending therethrough transversely of the longitudinal axis of the member and arranged to establish communication between the passages 4. The body portion 7 is cut away on one side as shown at 10, leaving a connecting portion having a flat face 11, this portion being semi-circular in cross section as shown in Fig. 3. The reduced end portions 8 have openings extending parallel with the passages 9, these openings being shown at 12. A passageway 13 extends from the cut away portion 10 to the outer surface of the cylindrical member 7 at a point 90 degrees from the ends of the passageway 9.

From the foregoing description of the various parts of the device, the operation thereof may be readily understood.

In Fig. 1 I have shown a water-closet bowl 14 and a pressure tank 15. The pipe 5 is an intake pipe which is controlled by a valve 16. The pipe 6 leads from the valve and communicates with the interior of the tank 15. The pipe 17 is a discharge pipe which leads from the tank to the valve and the pipe 18 is a short connection between the valve and the bowl.

Normally, the apparatus is in the position

shown in Fig. 1. The handle 19 is attached to the reduced portions 8 by passing the forked ends 19a through the openings 12. In the position shown in Fig. 1, the water will pass up through the pipe 5 through the passage 9 and into the tank 15. This tank is a closed tank, and when the pressure is balanced the flow of water will stop.

When it is desired to flush the tank it is only necessary to swing the handle 19 from the full line position shown in Fig. 1 to the dotted line position. This will turn the valve from the position shown in Figs. 2 and 3 so as to permit the flow of water through the valve from the pipe 17 to the pipe 18. Of course before the valve is thus turned, the water from the tank is prevented from entering the bowl since the valve portion 11 completely closed the opening. When the valve is shifted to the flushing position, the passage 9 is brought out of registration with the openings 14 and the latter are closed, so that there is no flow of water then into the tank. On reversing the movement of the handle the valve is again brought into its initial position, closing the communication between the tank and the bowl, and establishing communication between the source of supply of water and the tank, so that the latter is now filled.

In case it is desired to prevent the bursting of the tank, as in freezing, the handle 19 is swung into the dotted line position and left there. This drains the water out of the tank and it also establishes communication between the passage 13 and the pipe 6 leading to the tank so that any water in the latter is drained out, leaving the tank and pipes 6 and 17 leading thereto empty.

The valve may be used as an ordinary valve for flushing the bowl when the latter is connected to a source of water supply where a tank is not used. Thus in Fig. 6 the supply pipe 5 is connected by means of a member 20 with a pipe 21 leading to the valve. The latter has its openings 4 closed in any suitable means, as by screw plugs, not shown. On turning the handle the cylindrical valve is moved so as to permit the water from the supply to flush the bowl. On reversing the movement of the handle, the water will be shut off.

I claim:

A flush valve comprising a casing having a cylindrical bore, a cylindrical valve member having reduced extensions, caps for said casing, said reduced extensions passing through said caps, said casing having a pair of registering openings, a passageway through the body of said cylindrical valve for establishing communication with said registering openings, said casing having a second pair of registering openings disposed at right angles to the first named pair, said cylindrical valve member having a passage extending transversely with respect to the

first named passage for establishing communication between the second named pair of openings, means connected with the reduced portions for rotating the cylindrical valve member to bring either of said registering openings into communication at will, and a drain passage extending from said transverse passage and communicating with one of said first named openings when said transverse passage is in position to afford communication between said second named registering openings.
